UNITED STATES PATENT OFFICE.

JOSE MAS NADAL, OF HUMACAO, PORTO RICO.

WALL CONSTRUCTION.

1,391,567.

Specification of Letters Patent. Patented Sept. 20, 1921.

Application filed July 16, 1920. Serial No. 396,641.

To all whom it may concern:

Be it known that I, JOSE MAS NADAL, a subject of the King of Spain, and resident of Humacao, county of Humacao, Porto Rico, West Indies, have invented a new and Improved Wall Construction, of which the following is a full, clear, and exact description.

This invention relates to improvements in concrete wall construction, an object of the invention being to provide an improved re-inforced structure of this kind which will greatly reduce the cost of house building.

A further object is to provide a construction, either of the solid wall or hollow wall type, which will be strong and durable in use, and which will consist of a comparatively few parts, which may be readily assembled.

20 A further object is to provide a wall construction which may be assembled not only cheaply, but rapidly so that the cost of materials and the cost of labor are both substantially reduced.

25 A further object is to provide an improved type of panel shaped building blocks having four grooved faces, so that when a plurality of these blocks are assembled the grooves will form channels adapted to receive reinforcing rods.

With these and other objects in view, the invention consists in certain novel features of construction, and combinations and arrangements of parts as will be more fully hereinafter described and pointed out in the claims.

In the accompanying drawings:—

Figure 1 is a fragmentary view mainly in elevation of a wall constructed according to my invention with parts of adjoining walls shown in section.

40 Fig. 2 is a broken fragmentary view in horizontal section, of a solid wall construction, showing the way in which the outer walls are connected to the corner columns, and the way in which partitions are connected to the outer walls and to each other.

50 Fig. 3 is a fragmentary view in horizontal section, of a corner column and its connected parts, and illustrates a modification.

Fig. 4 is a broken fragmentary view in horizontal section illustrating a hollow wall construction, and

55 Fig. 5 is an enlarged perspective view of one of the panel blocks.

Referring in detail to the drawings, I em-

ploy a plurality of concrete slabs or panel blocks 1. These blocks are preferably square in shape, and relatively thin, their four meeting faces being provided with a 60 plurality of grooves 2.

The blocks are placed end to end, and one upon the other. Horizontal re-inforcing rods 3 are located in the groove 2, between each tier of blocks. Vertical re-inforcing 65 rods 4 are located in the grooves 2 between the columns of blocks. When the blocks are assembled, the grooves 2 will form channels for the re-inforcing rods 3 and 4.

It will be seen that at each corner of each block the vertical re-inforcing rods 4 and the horizontal re-inforcing rods 3 will cross. After the rods are arranged in pairs the parallel pairs of rods are preferably connected by tie wires 5. 70

At each point where the re-inforcing rods cross, that is at each corner of each block, cement or mortar 6 is located in the groove 2 around the re-inforcing bars, and tie wires. The cement or mortar is of course applied as 80 the wall is being constructed. After each pair of blocks has been laid the mortar is applied and the next tier laid on top.

The walls described above may be built upon any preferred kind of foundation 6'. 85 This foundation may be of brick or concrete, or the house may be built upon many kinds of foundations now commonly employed.

The vertical re-inforcing rods 4 are anchored in the foundation in any approved manner.

The corners of the building are formed of concrete columns 7. These columns are poured as the building is raised. Window 95 and door frames 8 are set in place as the building progresses, and secured by concrete or mortar to the panel blocks.

Referring particularly to the Figs. 1 and 2 of the drawings, I have illustrated four vertical reinforcing rods located in the corner columns. Upon each tier of panel blocks a tie wire 5 is located around all of the vertical re-inforcing rods in the column. The corner columns may be either flush with the 105 walls, as shown at 7 or may have their outer faces projecting slightly beyond the walls, as shown at 7'.

The horizontal re-inforcing rods 3 have their hooked ends 10 anchored in the corner 110 columns 10. Instead of employing only the usual form of horizontal re-inforcing rods,

3, horizontal re-inforcing tie rods 3' are also used, the bend of these tie rods being located against one of the vertical re-inforcing rods 4.

5 At the point where a partition 11 is joined to the wall, the panel blocks are spaced apart so that a column of concrete 12 may be poured in the wall. The ends of the horizontal re-inforcing rods of the partition 11 10 are embedded in the column 12. The partitions are constructed in substantially the same way as the walls, but thinner blocks are used in the construction. Where two partitions meet at right angles, the ends of 15 the partition blocks form a mold into which is poured a concrete column 13 having vertical re-inforcing rods embedded therein and secured together by tie wires.

Fig. 3 illustrates a modification, wherein 20 a corner column 14 is provided with five square vertical reinforcing rods 15. Two pairs of these rods are secured together by tie wires 16, and the other rod is tied to the bend of a single horizontal re-inforcing tie 25 wire 17, the only horizontal re-inforcement used in this construction.

Fig. 4 illustrates a hollow wall construction, wherein the inner wall 18 and an outer wall 18' are provided, both constructed of 30 panel blocks in the usual manner and having the air space between them. The horizontal reinforcing bars of both walls are anchored in a corner column 19, which joins the walls together.

35 The two walls may be further secured together by tie wires 20 connecting their vertical re-inforcing members and embedded in a poured column 21 located at a point where the partition 22 joins the hollow wall.

40 It is evident from the above description that I do not wish to confine myself to any particular arrangement of re-inforcing rods or tie wires, or any particular way of joining the partitions to the walls, but rather desire to 45 cover broadly the use of blocks having four grooved faces to receive horizontal and vertical re-inforcing rods, whether all of these blocks are assembled to form solid or hollow walls, or whether they be used to form 50 partitions.

The blocks may be made of any preferred

dimensions, it being understood that they are not to be so large as to be unwieldy or difficult to assemble.

It is apparent that various slight changes 55 and alterations might be made in the general form of the parts described without departing from my invention, and hence I do not limit myself to the precise details set forth, but consider myself at liberty to make such 60 slight changes and alterations as fairly fall within the spirit and scope of the appended claims.

What I claim as new is:—

1. In a building construction a pair of 65 intersecting walls comprising superposed tiers of rectangular blocks having grooves in all four of their edges, vertical and horizontal reinforcing rods in said grooves, vertical rods and horizontal stay wires around the rods at the intersection of the walls, the horizontal rods between the blocks coupled to the vertical rods at the wall intersection, and cementitious material embedding the 70 rods at the wall intersection and filling the 75 grooves in the blocks forming, when set, an integral wall interlock.

2. In a building construction, a pair of intersecting walls comprising superposed 80 tiers of rectangular blocks having grooves in all four of their edges, vertical and horizontal reinforcing rods in said grooves, vertical rods and horizontal stay wires around the rods at the intersection of the walls, the horizontal rods between the blocks extending 85 into the wall intersection, and cementitious material forming a vertical column at the wall intersection and filling the grooves of the blocks so that when said material is 90 set, it constitutes an integral wall interlock.

3. In a building construction, a pair of intersecting walls comprising superposed tiers of horizontal aligned blocks, all of the blocks having a plurality of grooves in all 95 four of their edges, vertical and horizontal reinforcing rods in the grooves of the blocks, said rods arranged in pairs and the rods of the respective pairs coupled together, a column intersecting tiers of said blocks, and cementitious material in the grooves of the 100 blocks and integral with the column.

JOSE MAS NADAL.
